UNITED STATES PATENT OFFICE.

HARRY ZIMMERMAN, OF FREDERICK, MARYLAND.

DESIGN FOR A SHUTTER-LOCK.

SPECIFICATION forming part of Design No. 28,284, dated February 15, 1898.

Application filed January 3, 1898. Serial No. 665,502. Term of patent 14 years.

To all whom it may concern:

Be it known that I, HARRY ZIMMERMAN, a citizen of the United States, residing at Frederick, in the county of Frederick and State of Maryland, have invented and produced a new and original Design for a Shutter-Lock, of which the following is a specification, reference being had to the accompanying drawings, forming a part thereof.

10 In the accompanying drawings I have illustrated my design embodied in a shutter-lock, in which—

Figure 1 is a perspective view. Fig. 2 is a front view. Fig. 3 is a top plan view, and

15 Fig. 4 is a side elevation.

The essential features of my design consist of a base having a general oval shape, a loop-like projection extending laterally from one edge of the oval base, and a curved tongue-shaped projection extending upward from

20 and at an inclination to the other edge of the oval base.

As illustrated in the drawings, A is the base of a general oval shape, and extending from the lower edge *a* thereof is the loop-like projection B, having an oval-shaped opening *b*, a portion of the edge of which is rounded, as at *b'*, while extending from the other edge *a'* of the base A is the tongue-shaped projection C, it being curved and at an inclination to the plane of the base A. Extending centrally through the tongue-shaped projection and the base is a curved rib C'.

What I claim is—

The design for a shutter-lock substantially as shown and described.

In testimony whereof I have signed my name to this specification in the presence of two subscribing witnesses.

HARRY ZIMMERMAN.
